SHIRT CUFF SLEEVE

Filed Oct. 25, 1928

UNITED STATES PATENT OFFICE

ABRAHAM MENZIN, OF NEW YORK, N. Y.

SHIRT CUFF SLEEVE

Application filed October 25, 1928. Serial No. 314,857.

This invention relates generally to shirts and has more particular reference to a sleeve construction for shirts.

The invention has for an object the provision of an article of the class mentioned which is of simple durable construction, desirable in use and efficient in action, and which can be manufactured and sold at a reasonable cost.

10. The invention proposes the use of a cuff attached to the lower end of a sleeve and arranged with a transverse pleat of a height equal to substantially one half the height of the cuff for permitting first one use of the 15 cuff and upon the opening up of the transverse pleat a second use of the cuff. Stitches are arranged transversely along the top of the cuff and longitudinally along the ends for normally holding the pleat in closed position 20 and breakable for permitting refolding of the cuff to its second condition. The sleeve is also provided with a plurality of longitudinal pleats connected with the top end of the cuff.

25. For further comprehension of the invention, and of the objects and advantages thereof, reference will be had to the following description and accompanying drawings and to the appended claims in which the various novel features of the invention are more particularly set forth.

In the accompanying drawing forming a material part of this disclosure:—

30. Fig. 1 is a fragmentary side elevational view of a shirt sleeve constructed according to this invention.

Fig. 2 is a similar view, but showing the cuff opened, disclosing the inner side thereof.

35. Fig. 3 is a fragmentary sectional view, taken on the line 3—3 of Fig. 2.

Fig. 4 is a fragmentary sectional view, taken on the line 4—4 of Fig. 2.

Fig. 5 is a fragmentary horizontal sectional view, taken on the line 5—5 of Fig. 1.

40. Fig. 6 is a view similar to Fig. 2, but showing the cuff in its second condition.

Fig. 7 is a fragmentary view of a portion of Fig. 2 illustrating a modification thereof.

45. Fig. 8 is a vertical sectional view, taken on the line 8—8 of Fig. 7.

Fig. 9 is a similar view to Fig. 4, showing another modification of the invention.

The reference numeral 10 indicates generally a sleeve with a slot opening 10' extending from the bottom thereof to a small distance from the elbow portion 11. The bottom portion of this sleeve is provided with a cuff 12.

50. The cuff 12 is made of double material sewn together along its edges by stitches 13 and the top of the cuff is attached to the material forming the sleeve by stitches 14. A transverse pleat 15 of a height equal to one half the height of the cuff is formed from the cuff material and is disposed on the inner side of 55 the cuff. This transverse pleat has a bottom bend 16 and a top bend 17. A top transverse row of stitches 18 secures the top bend 17 to the material of the sleeve and longitudinal end stitches 19 serve to hold the ends of the 60 pleat against the cuff. Instead of the stitches 19, snap fasteners 19' may be provided to hold the ends of the pleat against the cuff.

55. The cuff is provided with a button 20 arranged on one side of the slot opening 10' 75 and engageable with a buttonhole 21 in the other side of the slot opening for joining the ends of the cuff together. The sleeve material is provided with a button 22 engageable with a buttonhole 23 for holding the slot opening 80 of the sleeve together.

65. A plurality of longitudinal pleats 24 extend from the top edge of the cuff upwards in the material forming the sleeve for reducing the diameter of the sleeve at the bottom 85 portion and permitting expansion towards the upper portion of the sleeve. The material on one edge of the slot opening in the sleeve is bent as at 25 for forming a panel 26 and the free edge of this panel is turned in as 90 at 27 and sewn in by stitches 28. The other edge of the material forming the slot opening is also formed with a panel 29 formed by bending the material as at 30 and then sewing it down as at 31. A row of stitches 32 secure 95 the panels together near their top ends.

70. Generally gentlemen wear jackets and cover up their shirt sleeves leaving only the lower extremities slightly extending out of the sleeve of the jacket. After some use the 100

lower edge 31 of the cuff becomes worn and fringy. The owner of the shirt may then cut the longitudinal end stitches 19 and the transverse top stitches 18 for opening the transverse pleat 15. Then he may bend the 5 cuff at its center portion with one portion on the outer side as illustrated in Fig. 6. The cuff now has a new bottom 31' which has not as yet been worn out and it is readily seen 10 that this construction lengthens the life of the shirt.

It is pointed out that the cuff as formed in Fig. 6 is of the same height as that formed in Fig. 2 so as not to lengthen the sleeves of 15 the shirt during a change from one condition of the cuff to the second. The reason for maintenance of the same length is that the transverse pleat 15 was substantially one half the height of the original cuff and when 20 opened, the cuff may be bent in half for obtaining the same height of cuffs as originally. The lower bend 16 of the transverse pleat is formed with buttonhole openings 33 arranged for aligning with the buttonholes 21 and the 25 button 20 so that in the second position of the cuff it may be held together by the button 20.

In the modified form of the device illustrated in Figs. 7 and 8 a pocket 33^a has been formed for holding a reinforcement stiffening 30 and shaping member 34. This pocket is included between the top transverse stitches 18, the end longitudinal stitches 19 and short bottom transverse stitches 35 extending for a short distance inwards from the edge of the 35 cuff. The reinforcement stiffening member 34 is engaged in the opening beneath the pleat 15 and the transverse stitches 35 serve for holding it against displacement.

While I have shown and described the preferred embodiment of my invention, it is to 40 be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A sleeve for clothing, comprising material formed in tubular shape and having a slot connecting with one end, panels formed adjacent the slot by folding and sewing the said material, a cuff with a transverse pleat held in formation by stitches arranged for 50 being broken open, and said cuff being attached on the said material, longitudinal pleats formed in the material and starting at the cuff, and a means for securing the cuff and material adjacent the slot together.

2. In a cuff for the sleeves of clothing, a transverse pleat, longitudinal end stitches and a transverse row of top stitches for forming a pocket between the portions of the cuff forming said pleat, said pocket having its 65 opening at the bottom, and a short row of

transverse stitches at the bottom of the pocket for holding a reinforcing strip engaged in the pocket.

In testimony whereof I have affixed my signature.

ABRAHAM MENZIN.
